(57) **CLAIM**

The ornamental design for a charger adapter holder and connector, as shown and described.

DESCRIPTION

FIG. 1 is a perspective view of a charger adapter holder and connector showing my new design.

FIG. 2 is a front view thereof.

FIG. 3 is a rear view thereof.

FIG. 4 is a left end view thereof.

FIG. 5 is a right end view thereof.

FIG. 6 is a top view thereof.

FIG. 7 is a bottom view thereof.

FIG. 8 is a perspective view shown in a first position of use; and,

FIG. 9 is a perspective view shown in a second position of use.

The broken lines in the drawings represent unclaimed environmental subject matter and form no part of the claim.
